UNITED STATES PATENT OFFICE.

JOSEPH H. REAM, OF CANTON, OHIO.

RAILWAY-CHAIR.

SPECIFICATION forming part of Letters Patent No. 274,877, dated March 20, 1883.

Application filed October 28, 1882. (No model.)

To all whom it may concern:

Be it known that I, JOSEPH H. REAM, a citizen of the United States, residing at Canton, in the county of Stark and State of Ohio, have 5 invented certain new and useful Improvements in Railway-Chairs, of which the following is a specification, reference being had therein to the accompanying drawings.

Figure 1 is a perspective view of my improved 10 railroad-chair. Fig. 2 is a side elevation of the adjacent ends of two rails seated and fastened in the chair. Fig. 3 is a cross-section of the same.

The object of this invention is to provide a 15 chair for railroad-rails which shall hold the ends of the rails properly in place in such manner as to avoid the necessity of fish-plates or bolts.

In the drawings the chair is represented as 20 being formed of a bed or base plate, a , side flanges, a' , and studs a^2 a^3 , projecting upwardly from the base-plate a and inwardly from the side flanges, a' , these parts being formed integrally of cast metal or wrought. In the 25 base-plate a , along the central portion thereof, are formed a series of countersunk apertures, a^3 , for the purpose of receiving and concealing the heads of spikes B for holding the chair in position upon the ties independently of other 30 fastening devices.

The ends of the railroad-rails B' are of substantially the ordinary character, except that they are formed with recesses corresponding in position to the studs a^2 and adapted to engage therewith, the bottoms of the rails being 35 of substantially the same width as the bed-plate a of the chair, the side flanges, a' , being (when the parts are in place) in close proximity to the sides of the bottom of the rail. The 40 recesses in the rail are somewhat larger than

the lugs or studs a^2 , so as to allow a space for the movement of the rails when they are contracting or expanding.

The chair is supported in two or more ties, as shown in Fig. 2, and to them it is firmly 45 fastened by means of the spikes B. In addition to the spikes B the spikes D D are employed to hold the chair and rails in place. These spikes are substantially like those ordinarily employed to spike railroad-rails, the 50 heads being made of such length that they will overlap the flanges a' and bear upon the flange of the rail, thus holding the rail securely upon the bed-plate of the chair.

When a chair of this kind is used the rails 55 are held in place with perfect firmness, and at the same time avoid entirely the necessity of the ordinary fish-plates and bolts, though retaining in the fastening all of the advantages incident to the use of said plates and bolts. 60

What I claim is—

1. The herein-described railway-chairs having the base or bed plate a , the side flanges, a' , the countersunk apertures a^3 for fastening to the ties, and the studs or lugs a^2 for engaging 65 with the rails, substantially as set forth.

2. The combination of the railroad-rails having notches formed in the sides of the flanges, the chair having the bed-plate a , the side flanges, a' , and the lugs or studs a^2 , adapted to 70 engage with the notches in the rails, and the spikes D, whose heads overlap both the flange a' and the flange of the rail, substantially as set forth.

In testimony whereof I affix my signature in 75 presence of two witnesses.

JOSEPH H. REAM.

Witnesses:

HENRY FISHER,
GEO. E. BALDWIN.
